UNITED STATES PATENT OFFICE

FRANCIS REGINALD BEAMAN WHITEHOUSE, OF HARBORNE, BIRMINGHAM,
ENGLAND

APPARATUS FOR PLAYING A RACE GAME

Application filed March 14, 1929, Serial No. 347,122, and in Great Britain September 22, 1928.

This invention relates to apparatus for playing a race game, the apparatus being of the kind which includes a reciprocating track upon which model horses or other movable figures are placed for the purpose of playing a race game.

In this kind of apparatus it has already been proposed to employ a track of flexible material connected by springs or elastic members to clips or clamps adapted to be attached to the edge of a table and having mechanical means at the opposite end for intermittently pulling the track endwise against the pull of the springs or elastic members and releasing it so as to produce the necessary reciprocating motion.

The primary object of the present invention is to provide improved apparatus whereby a more interesting game may be played than hitherto.

One of the features of the present invention is to provide a flexible track with means for impeding the progress of the playing pieces during the game. Such impeding means may be in the form of holes or indentations in the track, or may take the form of small blocks or obstacles attached to the track and adapted to project above the upper surface of the track, or they may take any other suitable form. All of such impeding means will be hereinafter referred to as "obstacles." The obstacles are preferably arranged in spaced relationship in one or more rows extending across the track and the obstacles in adjacent rows may be directly opposite to each other or they may be staggered in relation to each other.

In apparatus of the kind referred to for producing the movement of the track it has already been proposed to use mechanical means. A further feature of the present invention is to provide an open ended or open sided box or housing for such mechanical means this box or housing being adapted to be placed on the table and attached thereto preferably by clamps or clips.

When using such a housing one end of the track necessarily enters the housing and it is a further feature of this invention to provide means whereby the track adjacent this

end is retained in the same horizontal plane as the remainder of the track instead of rising in an incline where it enters a housing.

In accordance with this feature of the present invention the end portion of the track which enters the housing is raised up above the main portion of the track by means of a distance strip extending across the track adjacent the housing and beyond the winning post or the line on the track representing the winning post.

A further feature of the present invention has for its object to enable the apparatus to be used on various lengths of table and in accordance with this part of my invention the elastic connections to one end of the track are provided with connecting strips which are perforated with a row of holes while spring or other clips or brackets are provided for attaching to the end of the table, the said clips or brackets including upwardly disposed posts over which any one of the holes in the connecting strips may be placed so that the tension on the track produced by the elastic members can be adjusted without difficulty.

Referring to the drawings:—

Figure 1 is a perspective view showing one form of the apparatus.

Figure 2 is a section on line 2—2 of Figure 1.

Figure 3 is a plan view showing the means for operating the track.

Figure 4 is a plan view showing a modified form of means for operating the track.

Fig. 5 is a sectional view showing one form of obstacle.

Figure 6 is a perspective view showing another form of obstacle.

Figure 7 is a perspective view showing another form of obstacle.

Figure 8 is a perspective view showing one of the clips.

In the construction illustrated the track 1 may be made of woven or other flexible material and at its forward or winning post end the upper surface of the track is provided with a distance strip 2 extending across the track. This distance strip may be made of wood and the continuation or extreme forward end 3 of the track is attached to the up-

per side of this distance strip so that it is raised above the plane of the main part 1 of the track.

The extreme forward end of the track 5 projects into a housing or box 4 and may be stiffened by or formed of a sheet of cardboard or other rigid material.

At its centre this material is slotted at 10 and engages over a straight sided block 6 so that it is guided thereby so that it can reciprocate in the direction of the length of the track.

The edges 7 of that part of the track which projects into the box or housing converge towards each other.

15 Rotatably mounted upon the guide 6 fixed to the housing or box is a cam wheel 8 of hexagonal form having a spindle 9 which projects through the top of the box 4 where it is provided with a crank 10 by which it may be turned.

The spindle 9 has a head 11 located in a recess in a block 6 secured to the bottom of the box 4.

20 The stiffened part 3 of the track which projects into the box or housing 4 is provided with a projection 13 preferably having an inclined surface 14, i. e. a surface inclined to the centre line of the track and this projection is engaged by the teeth or cams upon the rotary 25 wheel 8, the arrangement being such that when the wheel is rotated the corners thereon move the track bodily in an endwise direction until the side engaging with the inclined 30 projection 13 passes the projection. Each 35 time this occurs the track is drawn backwardly very smartly by the springs or elastic members 15 at the other end of the track so that the forward movement of the track is comparatively slow while the backward movement is a quick sharp jerk.

The under-side of the box or housing 4 at the forward end of the track is preferably provided with a felt or other covering of soft material so that it will not damage the surface 45 of a table and the end of the box or housing carries a pair of U shaped clamps 16 having screws 17 which can be made to engage with the under surface of the table top.

Instead of the hexagonal wheel 8, a wheel 50 of ratchet form as shown at 27 in Figure 4 may be used and this may engage with a curved surface 29 on a block 30 attached to the track.

At the opposite end of the track elastic 55 bands 15 or springs are provided which are secured to connecting strips 18 each of which has a series of spaced perforations 19 any one of which is adapted to be engaged over the posts 20 of spring wire clips 21 adapted to 60 be attached to the opposite edge of the table.

In the case of an apparatus intended for models of horses, dogs or other objects, one, two, three or more rows of obstacles may be provided intermediate the starting point and 65 the finishing point and these obstacles may

take the form of small cylindrical blocks 22 of wood attached to the upper surface of the track in spaced relationship and in rows extending across the track.

The blocks may be attached by metal plates having spikes passing through the track as shown in Figure 5 and instead of being cylindrical they may be of segmental form as shown at 23 in Figure 6 with their flat sides attached to the track by adhesive or by other means so that their side surfaces 75 24 are parallel with the edges of the track.

Instead of using small blocks of wood or other material for the obstacles the track may be provided with a row of metal eyelets 25 as 80 shown in Figure 7, the eyelets being inserted in the material of the track in spaced relationship and in rows extending across the track. These eyelets may be circular or of any other suitable form and it is found in 85 practice that they project above the surface of the track sufficiently to cause the moving object thereon to be delayed or possibly thrown over should the object come into contact with them.

90 Instead of spacing the obstacles in a regular manner as has been described, they may be spaced irregularly if desired or the rows may be staggered.

95 Any suitable form of playing piece may be used. Model horses 31 are shown, but model dogs or vehicles may be employed if desired.

100 In another form of the apparatus the track is made of sufficient width to cover the whole surface or practically the whole surface of a table. The means of producing motion may be the same as that described and the elastic connections at the opposite ends of the track may be the same.

105 In such an arrangement, however, the models or figures which are raised upon the track may take the form of small model ships or boats and the obstacles may be marked or shaped and may take the form of islands either spaced regularly or irregularly upon the track between the starting end and the finishing end.

110 In all cases the finish may be marked by a simple line 26 extending across the track, or compartments may be provided into which the race figures will come to rest.

What I claim then is:—

115 1. Apparatus for playing a race game comprising a flexible track adapted to be laid out upon a support, playing pieces, means for actuating said track in a manner to cause the playing pieces to travel along the track and a number of rows of obstacles on said track 120 which have to be passed by the playing pieces during the game, and an open sided housing adapted to house the track actuating means, an end part of said track being raised above the level of the main part of the track and being adapted to enter the said housing and 125 130

having a slot, a projection on said housing adapted to work in said slot and guide the said end of the track, a member on said end part of the track, a rotatable cam adapted to engage 5 said member and cause the track intermittently to be moved in an endwise direction, means for returning said track to its normal position after each of such endwise movements, and means for attaching one end of 10 said track and the said housing to the said support.

2. Apparatus for playing a race game comprising a flexible track adapted to be laid out upon a support, playing pieces, means 15 for actuating said track in a manner to cause the playing pieces to travel along the track, and means for impeding the progress of the playing pieces during the game, said track actuating means being associated with one 20 end of the track, an open sided housing adapted to house the track actuating means, clamping means for attaching said housing to said support, elastic members attached to the end of the track opposite to the end with 25 which the said housing and track operating means are associated, clip members adapted to be attached to said support and perforated connecting strips attached to said elastic member and adapted to be adjustably 30 connected to said clips and said elastic members being adapted to retain said track extended and under tension.

3. Apparatus for playing a race game comprising a flexible track adapted to be laid out upon a support, playing pieces adapted to be placed on said track, means associated with one end of the track for causing the track to make a reciprocating movement in a manner to cause the playing pieces 40 to travel along the track, a number of rows of obstacles attached to said track and which have to be passed by the playing pieces during the game, an open sided housing adapted to house the track actuating means, clamping means for attaching said housing to said 45 support, said track operating means comprising an end part of said track raised above the level of the main part of the track and adapted to enter the said housing and having 50 a slot, a projection on said housing adapted to work in said slot and guide the said end of the track, a member on said end part of the track, a rotatable cam adapted to engage 55 said member and cause the track intermittently to be moved in an endwise direction, means for returning said track to its normal position after each of such endwise movements, comprising elastic members attached to the end of the track opposite to the end 60 with which the said housing and track operating means are associated, clip members adapted to be attached to said support, perforated connecting strips attached to said elastic members and adapted to be adjustably 65 connected to said clips and said elastic mem-

bers being adapted to retain said track extended and under tension.

4. Apparatus for playing a race game comprising a flexible track, an abutment near one end of the track, operating means for intermittently moving the track in an endwise direction, said operating means engaging 70 said abutment, a support for said operating means, clamping means for fixing said support, elastic members operating upon the end of the track opposite to that where said operating means are situated, clamping means for fixing said elastic members, and playing pieces for moving on said track.

5. Apparatus for playing a race game comprising a flexible track, an abutment near one end of the track, operating means for intermittently moving the track in an endwise direction, said operating means engaging 80 said abutment, a support for said operating means, clamping means for fixing said support, elastic members operating upon the end of the track opposite to that where said operating means are situated, connecting strips attached to said elastic members, clamps adjustably associated with said connecting strips, and playing pieces for moving on said track.

6. Apparatus for playing a race game comprising a flexible track, an abutment near one end of the track, operating means for intermittently moving the track in an endwise direction, said operating means engaging 90 said abutment, a support for said operating means, clamping means for fixing said support, elastic members operating upon the end of the track opposite to that where said operating means are situated, clamping means for fixing said elastic members, said track forming the sole means of connection between 95 said support and said elastic member.

In witness whereof I affix my signature.
FRANCIS REGINALD BEAMAN WHITEHOUSE.
